DESIGN FOR AN EMULSIFYING MACHINE FRAME OR THE LIKE

Albert Richard Bannister, Sunbury-on-Thames,
England, assignor to British Emulsifiers, Lim-
ited, Teddington, England, a corporation of
Great Britain

Application October 28, 1935, Serial No. 59,250

Term of patent 3½ years

To all whom it may concern:

Be it known that I, Albert Richard Bannister, a subject of the King of Great Britain and Ireland, residing at 14, Darby Crescent, Sunbury-on-Thames, in the county of Middlesex, England, have invented a new, original, and ornamental Design for an Emulsifying Machine Frame or the like, of which the following is a specification, reference being had to the accompanying drawing, forming part thereof.

Figure 1 is a side elevation of the article showing my design;

Figure 2 is a top plan view;

Figure 3 is an end elevation thereof.

I claim:

The ornamental design for an emulsifying machine frame or the like, as shown.

ALBERT RICHARD BANNISTER.
